UNITED STATES PATENT OFFICE

2,454,383

REFINING OF HYDROCARBON DISTILLATES

Jacob Benjamin Heid, Oak Park, Ill., assignor to
Universal Oil Products Company, Chicago, Ill.,
a corporation of Delaware

Application September 29, 1945, Serial No. 619,409

2 Claims. (Cl. 196—32)

1

This invention relates to the refining of hydrocarbon distillates and more particularly to an improvement in the caustic treating process for the removal of mercaptans and acidic bodies from gasoline.

While the invention is particularly applicable to the treatment of gasolines containing mercaptans, it is also applicable to the treatment of other hydrocarbon distillates, such as naphtha, kerosene, Diesel oil, lubricating oil, etc., for the removal of acidic compounds and particularly sulfur compounds.

Gasolines containing mercaptans are treated with alkali metal hydroxides to remove mercaptans. This process is known as the caustic treating process and in general comprises contacting the gasoline with caustic solution at substantially atmospheric temperature in a system wherein intimate contacting of the gasoline and caustic is obtained. One particularly preferred method is to pass the gasoline in an upward stream countercurrently to a descending stream of caustic in a tower containing suitable packing in order to effect intimate contact of the gasoline and caustic. The process is normally operated under sufficient pressure to maintain the gasoline and caustic solutions in liquid phase. The treated gasoline is withdrawn from the upper portion of the contact tower, and the spent caustic is withdrawn from the lower portion thereof and subjected to suitable regeneration to recover the caustic for reuse in the process.

I have found that with gasolines having a high content of carboxylic acids, including naphthenic and/or aliphatic acids, foaming occurs in the caustic treating tower, with the result that separation of the caustic solution containing mercaptans from gasoline does not readily occur, and the treated gasoline withdrawn from the treating tower is not of the desired improved quality normally expected from the caustic treatment.

An object of the present invention is to avoid the difficulty hereinbefore set forth and to provide a process for the caustic treatment of gasolines containing high naphthenic and/or aliphatic acids wherein ready separation of the hydrocarbon distillate and caustic solution is effected in the treating tower.

In a broad aspect the present invention relates to a process for refining a hydrocarbon distillate containing mercaptans which comprises treating said distillate with an alkaline earth metal hydroxide and thereafter treating said distillate with an alkali metal hydroxide.

In a specific embodiment, the present inven-

2

tion relates to a process for refining gasoline containing mercaptans and carboxylic acids which comprises treating said gasoline with a barium hydroxide solution and thereafter treating said gasoline with a caustic solution.

In accordance with the invention, the gasoline to be treated is contacted with an alkaline earth metal hydroxide solution. While solutions of calcium hydroxide or strontium hydroxide may be employed, barium hydroxide solutions are preferred. The pretreatment may be effected at substantially atmospheric temperature, which generally will be within the range of about 50 to about 100° F. The pretreatment suitably may be effected in a prewash tower containing suitable packing material to insure intimate contact of the gasoline and reagent, in which operation the gasoline is preferably pumped upward countercurrently to a descending stream of reagent. Another method of contacting is a batch operation, in which case a suitable level of the alkaline earth metal hydroxide solution is disposed in the prewash tower, likewise preferably containing packing material, and the gasoline is passed upwardly through the body of reagent.

The gasoline so treated is then contacted with an alkali metal hydroxide, such as sodium hydroxide, potassium hydroxide, etc., in any suitable type of apparatus which advantageously comprises an absorber tower containing suitable packing to insure intimate contact of the gasoline and caustic. The gasoline likewise is preferably passed upwardly countercurrently to a descending stream of caustic solution.

It is understood that, in place of the packed towers hereinbefore set forth, any other suitable mixing and contacting devices may be used such as a series of mixers and settlers, orifice plates, etc. These various methods of contacting are well known in the art and need not be described here in detail.

The accompanying diagrammatic drawing illustrates one specific method of conducting the process of the present invention. It is understood that the broad scope of the present invention is not limited to the specific operation illustrated in the drawing.

Referring to the drawing, the hydrocarbon distillates charging stock is introduced to the process through line 1, containing valve 2, and is supplied to prewash tower 3, wherein it is contacted with an alkaline earth metal hydroxide at substantially atmospheric temperature and at superatmospheric pressure which generally will

be between about 10 to about 50 pounds per square inch.

In the case illustrated herein, tower 3 comprises a batch-type operation, in which operation the tower is filled to the desired level with a solution of alkaline earth metal hydroxide and the gasoline is passed therethrough. The operation is continued until the alkaline earth metal hydroxide solution becomes spent for the purpose intended. In general, the consumption of alkaline earth metal hydroxide will be about one pound per 100 to 200 barrels of gasoline treated, depending upon the percentage of acidic bodies in the gasoline undergoing treatment. After the reagent becomes spent, the spent reagent is withdrawn and a new supply of reagent is charged to the tower. The particular case illustrated comprises a prewash tower containing a packing material to insure intimate contacting of gasoline and reagent. Any suitable packing material which does not react with the solution in tower 3 may be employed; a particularly suitable packing material comprising carbon Raschig rings. Other suitable packing materials may be employed such as bubble trays, baffle plates, etc.

In the case of a batch-type operation as illustrated in the drawing, the spent alkaline earth metal hydroxide solution may be withdrawn from the lower portion of zone 3 through line 4 and valve 5, to disposal as desired.

In the case of continuous-type operation, the alkaline earth metal hydroxide may be continuously or intermittently withdrawn from the bottom of tower 3, supplied to the solution tank, not illustrated, wherein it is maintained at the desired concentration and then recirculated to the upper portion of tower 3.

An insoluble precipitate, comprising alkaline earth metal hydroxide and naphthenic and/or aliphatic acids, forms in tower 3, thus preventing the acids from entering the subsequent caustic treating step and causing undesired foaming therein. In the absence of such a pretreatment, these acids form gels in the caustic solutions and result in foaming and caustic carryover from the caustic treating tower. The caustic solution becomes a soapy mass of bubbles and will not separate from the gasoline, with the result that the caustic solution is carried over with the gasoline to the gasoline storage facilities.

When the gasoline also contains hydrogen sulfide, it preferably is given a preliminary caustic wash to remove hydrogen sulfide and this may be accomplished, in the case herein illustrated, by passing the gasoline from tower 3 through line 6 and valve 7 to caustic scrubber 8. Scrubber 8 is illustrated as the same general type as tower 3, it being understood that it may comprise any suitable other mixing and contacting apparatus. In this tower, hydrogen sulfide reacts with the sodium hydroxide to form sodium sulfide. The caustic employed is preferably of 5 to 15° Bé. gravity. The caustic containing the sulfide may be withdrawn from the lower portion of scrubber 8 through line 9 and valve 10 to storage or elsewhere as desired, and the gasoline, free from hydrogen sulfide, is withdrawn from the upper portion of tower 8 through line 11.

Several other modifications not illustrated are also comprised within the scope of the present invention. In one modification the prewash and caustic scrubbing may be effected in a common zone by utilizing a mixture of alkaline earth metal hydroxide and caustic. In this case, caustic scrubber 8 may be omitted and the prewashed

gasoline may be supplied from line 6 through line 12 and valve 13 direct to the absorber 14. When the gasoline is free from hydrogen sulfide or has been otherwise treated to remove the hydrogen sulfide, caustic scrubber 8 may be omitted and the prewashed gasoline passed through line 12 and valve 13 direct to absorber 14.

Caustic scrubbing in zone 8 may be effected at substantially atmospheric temperature and under sufficient pressure to effect movement of the gasoline through the system. The partially treated gasoline from line 11, in one embodiment of the invention, is passed through valve 15 to heater 16. Heater 16 may comprise any suitable means for raising the temperature of the gasoline to about 135-185° F. and thus may comprise a heat exchanger or externally fired heater. The heated gasoline is then passed through line 17 and valve 18 to absorber 14.

In another modification the partially treated gasoline from line 11 which is at substantially atmospheric temperature, may be passed through by-pass line 19, valve 20, line 17 and valve 18, to absorber 14, and the mercaptan removal effected at substantially atmospheric temperature.

In the case here illustrated, absorber 14 comprises a packed tower of the same general design as towers 3 and 8, and the gasoline is countercurrently contacted with the caustic solution therein. It is understood that any other suitable contacting means may be employed within the scope of the invention. The gasoline substantially free of mercaptans is removed from the upper portion of absorber 14 through line 21 and valve 22 to storage or any further treatment as desired.

The spent caustic solution from absorber 14 is withdrawn from the lower portion thereof through line 23 and valve 24 and is partially heated in exchanger 25, directed through line 26 and valve 27 to heater 28 and then passed through line 29 and valve 30 to regenerator 31. Heater 28 may be of any desired design and thus may comprise a suitable heat exchanger or externally fired heater in order to raise the temperature of the spent caustic solution to that suitable for effecting regeneration. In general, the temperature employed in regenerator 31 will be just below the boiling point of the solution and will, of course, vary with the gravity of the particular solution being employed. In general, the gravity of the solution employed in absorber 14 will be of 15 to 35° Bé. and the temperature in regenerator 31 will be about 220 to about 250° F.

In the case illustrated, regenerator 31 is of similar design to absorber 14 and contains a suitable packing material, it being understood that other suitable regenerating means may be employed. To effect regeneration of the caustic solution and the separation thereof from mercaptans, steam or other suitable stripping medium is introduced through line 32 containing valve 33. An overhead stream comprising vaporous mercaptans and water is withdrawn from the upper portion of regenerator 31 through line 34 and valve 35. The regenerated caustic solution is withdrawn from the lower portion of regenerator 31 through line 36 and valve 37, and is directed through heat exchanger 25, line 38 and valve 39 to pump 40, by means of which it is directed through line 41 and valve 42 to cooler 43. In cooler 43, the regenerated caustic solution is cooled to the desired temperature which in one embodiment of the invention is substantially atmospheric temperature and in another embodiment of the invention is between 135 and 185° F. The cooled regenerated caustic

is then directed through line 44, containing valve 45, to the upper portion of absorber 14, for further use in the manner hereinbefore set forth.

While the description hereinbefore set forth has been directed primarily to aqueous solutions of alkali metal hydroxides, the features of the present invention are also applicable to the treatment of non-aqueous solutions of alkali metal hydroxides, such as alcoholic solutions, and also to alkali metal hydroxide solutions containing a modifying agent such as the well-known Unisol process in which the treating solution comprises a mixture of caustic and methanol, as well as alkali metal hydroxide solutions containing solutizers, such as tripotassium phosphate, potassium isobutyrate, alkanol amines, etc.

The following example is introduced to illustrate further the novelty and utility of the present invention but not with the intention of unduly limiting the same.

A gasoline obtained by thermally cracking North Texas topped crude and containing 0.025% mercaptan sulfur, 0.04% by weight of naphthenic acids and phenols and a trace of hydrogen sulfide is first passed in contact with barium hydroxide solution to remove the naphthenic acids. The gasoline is then scrubbed with a 12° Bé. caustic solution to remove the last traces of hydrogen sulfide, after which the gasoline is treated with caustic of 25° Bé. in a process of substantially the design illustrated in the drawing to remove mercaptans.

Prior to the use of the barium hydroxide pre-treatment, foaming occurred in the mercaptan absorber with the result that the gasoline with-

drawn therefrom contained caustic solution. However, when utilizing the barium hydroxide pretreat, no foaming was encountered and ready separation of the treated gasoline was effected.

5 I claim as my invention:

1. A process for refining hydrocarbon distillate containing mercaptans, hydrogen sulfide and an amount of carboxylic acids such that objectionable foaming occurs in the contacting of the distillate with caustic solution of a strength to remove the mercaptans, which comprises treating said distillate with a solution comprising a mixture of barium hydroxide and caustic of 5 to 15° Bé. to remove hydrogen sulfide and carboxylic acids, and thereafter treating said distillate with a caustic solution of 15 to 35° Bé. to remove mercaptans.

2. The process of claim 1 further characterized in that said distillate comprises gasoline.
